UNITED STATES PATENT OFFICE

HENRY B. PETIT, OF DETROIT, MICHIGAN, ASSIGNOR TO GEORGE M. HOLLEY, OF DETROIT, MICHIGAN

VAPORIZER FOR INTERNAL-COMBUSTION ENGINES

Application filed May 23, 1927. Serial No. 193,499.

This invention relates to that type of vaporizer in which the fuel is vaporized with a small proportion of the total air and is then subsequently diluted before being admitted 5 to the inlet manifold.

The object of this invention is to provide convenient means whereby the timing and the quantity of the admission of additional fuel can be adjusted so as to take place at the 10 most opportune moment, and in the correct amount, so that the mixture may be maintained at its most efficient ratio at all rates of air flow to the engine.

In the present state of the art there is 15 considerable difficulty in making a device of the general type indicated above to fit any given automobile or motor truck, and this difficulty is especially serious when only a limited time can be devoted to a particular job. 20 A good deal of fitting is necessary, and therefore a great deal of the selling cost of such a device represents the amount of money necessary to reimburse the manufacturer for his experimental work in fitting the device. 25 By the means disclosed in this invention the fitting of the vaporizer to satisfy given conditions is much simplified.

Figure 1 shows a cross sectional elevation of the vaporizer.

30 Figure 2 shows the corresponding cross sectional elevation of the mixing chamber to which the vaporizer supplies the rich mixture.

(Note) Figure 1 shows the invention proper; Figure 2 is merely a complementary figure.

In Figure 1, *a* is the primary air tube through which air is conducted and heated as it passes through an exhaust manifold *b* 40 to a primary air passage *c* communicating with the vertical passage *d*, into which the fuel nozzle *e* discharges under the aspirating effect of the air passing up the passage *f*, which is a continuation of *d* and leads to the 45 horizontal passage *g*. (These passages *c*, *d*, *f*, and *g* are drilled passages in the casting *o*, which carries the nozzle *e*.) The passage *g* discharges a mixture of air and fuel against an exhaust heated plate *h*, which is the subject of Patents No. 1,547,474 and No. 1,562,670.

As the fuel flows against the plate *h* it is vaporized and discharges through *j* as a more or less completely vaporized fuel entrained with a small quantity of air heated to the same temperature. The casting *o* carries the float 55 chamber, comprising the bowl *p*, float *q*, and float mechanism not shown. The casting *o* is cast integral with the cover *i*, which forms with the plate *h* and exhaust manifold *b* the vaporizing passage *t* which communicates 60 with the vapor outlet *j*.

The passage *k* for the additional fuel is drilled in *o* parallel to the passage *f* and communicates with the fuel in the float chamber *p* below the constant level *y*—*y*. At its 65 upper end the passage *k* terminates in a restriction or nozzle 5 which discharges into a small chamber 4, which communicates through an opening *l* with the passage *g*. This chamber 4 at its outer end is air bled 70 or vented through the passage 3 in the plug 2, which communicates with the atmosphere which provides the means for delaying the flow of the fuel up *k* until a certain minimum depression exists in *g*. 75

In Figure 2 this mixture flowing through *j* is shown communicating with the mixture chamber through the outlet 12, which discharges into the throat 6 of the Venturi tube 7. An automatic air valve 24 controls the 80 air which enters the air entrance 17 and maintains the flow of vapor through 12 at the lower air speeds. The opening of the air valve 24 is checked by the stud 25, the length of which can be adjusted. The throttle lever 85 8 controls the throttle valve 9, in which is the air and fuel to the mixture outlet 10. To facilitate starting the air entrance is controlled by the choke valve 16 mounted on a rod 18. 90

Referring to Figure 1, the novel features of this invention reside generally in the provision of:—

An additional fuel nozzle 4 which discharges the correct amount of fuel into *g* 95 through which is located above the level *y*—*y* of the float chamber *l*, and specifically in the provision of:—

A plug 2 which has an orifice 3 communicating with the atmosphere, the size of which 100

regulates the time at which the fuel nozzle 5 comes into operation by breaking the suction in 4 until the opportune moment arrives for admitting additional fuel therein.

5 Operation.—When, in the operation of the engine, it is found that on opening the throttle the engine tends to back-fire due to the fuel from 5 coming in too late, an earlier discharge of fuel through 7 is obtained by reducing the size of the plug 2. If there is a tendency for the fuel to come in too soon, which fault is indicated by the characteristic "bump" which then takes place, plug 2 is removed and the orifice 3 enlarged, or 2 is 10 replaced by a plug having a larger vent opening therein. Hence it is possible to make a fitting without varying the air valve 24, and by merely having a number of plugs 2 having various drilled sizes 3 therethrough, 15 which are interchangeable.

20 In order to give an idea of the relative size of the various passages, if the annulus around the nozzle e is equal to a $\frac{3}{16}$ " drill, and f is a $\frac{1}{4}$ " drilled passage, and the restriction in e is equal to a #59 (.041") drill, then 1. will be a #55 (.052") drill, 3 a #50 (.07") drill and 5 a #55 drill. Slight variation from these dimensions will enable the 25 fuel from the nozzle 5 to be added to that from e without disturbing the smooth operation of the engine to which the vaporizer is fitted.

29 What I claim is:—

30 In a vaporizer adapted for use with an internal combustion engine of the type in which a primary heated rich mixture is diluted with cold air, a primary rich mixture passage, a fuel nozzle discharging therein substantially at the level in the float chamber 35 to form the primary rich mixture, a small chamber communicating with said rich mixture passage, a second fuel nozzle discharging into said chamber and thence into said rich mixture passage at a point above the 40 level in the float chamber, a restricted orifice communicating with the said small chamber and with the atmosphere, whereby the depression in the primary rich mixture passage at which this second nozzle commences to 45 feed therein is regulated.

50 In testimony whereof I affix my signature.
HENRY B. PÉTIT.
